UNITED STATES PATENT OFFICE.

WALTER O. LUM, OF BROOKLYN, NEW YORK, ASSIGNOR TO BLO-DRY INCORPORATED, OF SYRACUSE, NEW YORK, A CORPORATION OF NEW YORK.

DRYING DEVICE FOR THE LAVATORY.

Application filed July 28, 1921. Serial No. 488,261.

To all whom it may concern:

Be it known that I, WALTER O. LUM, a citizen of the United States, residing at Brooklyn, in the county of Kings and State of New York, have invented certain new and useful Improvements in Drying Devices for the Lavatory, of which the following is a specification.

This invention relates to mechanical drying devices for taking the place of towels (paper or fabric) in public lavatories or the wash rooms of office and factory buildings. While devices have heretofore been proposed making use of a heated current of air, such devices have heretofore been large and expensive and easily damaged by careless users. It is one object of this invention to simplify existing constructions of electric driers of this character and to render them as near fool proof as possible. A further object of the invention, allied with the first, is to render the shutting off of the current through the heating coil entirely automatic and out of the control of the user, so that there will be no danger of the current remaining on after the user has dried his hands. A still further object of the invention is to so construct the inlet and outlet for the air as to prevent the possibility of boys or other mischievous persons stopping the circulation through the machine by placing their hands over either aperture.

Further objects of the invention will become apparent as the description proceeds.

Referring to the drawings, in which what I now consider the preferred forms of my invention are shown:

Fig. 1 is a vertical section through the drier.

Fig. 2 is a vertical section, partly in elevation, taken at right angles to Fig. 1.

Fig. 3 is a detail of the cam and lever for operating the circuit breaking switch.

Fig. 4 is a wiring diagram showing the preferred connections between the master switch, motor, heating coil and circuit breaking switch.

Fig. 5 is a side elevation of said circuit breaking switch.

Fig. 6 is a plan view of the same.

Figs. 7, 8 and 9 are wiring diagrams of three modified forms of connections.

The device is shown as enclosed within a housing 1 which may be provided with a foot

2 (broken away in Fig. 1) for securing it to the wall. Said housing is shown as made in two parts, the cover 3 being detachable and carrying the nozzle or outlet pipe 4. Said pipe is preferably covered at its outer end 60 by a stout wire screen or guard 4' of convex shape so that the outlet cannot be completely covered by the hand, for the purpose above described. Within said housing is an inner casing 5 enclosing the blower 6 and 65 supporting the driving motor 7, the motor casing being shown as secured directly to said casing as by set screws 8. Said casing is extended to one side to form an inner nozzle or outlet pipe 9 so that the nozzle 70 of the device is in two parts, the outer portion 4 being integral with the cover or housing. A slip joint 10 is provided between the two portions to ensure a good fit. I also prefer to mount the heating unit 11 directly 75 in the nozzle and preferably within the inner or stationary portion thereof, thereby applying the heat to air as close as possible to the point where it is used and avoiding the heating up of the whole 80 interior of the casing and its motor. Said coil 11 may be composed of any standard "heater" wire and preferably has incorporated therein a fusible section 12 adapted 85 to open the coil circuit upon rise in temperature of the coil beyond safe limits from any cause. A thermometer 14 may also be located with its bulb 15 within the nozzle to show to the user the temperature of the issuing air. Users of machines of this nature 90 very often complain that the air feels cold, when it is in reality warm, as the evaporation of the moisture on their hands makes it feel cold. Suitable inlets for the air are shown at 16 and 17. If more than 95 one are provided it is not so necessary that they be covered by a convex guard 4", since the stoppage of one hole will not shut off the air supply. After entering the housing 1, the air is drawn into the central aperture 18 of casing 5 by the blower 6 and is forced outwardly through the nozzle 9. A push button for the operator or user is shown at 19 but as stated above, I prefer to provide an automatically operated 105 switch for breaking at least the coil circuit and preferably both the coil and motor circuits. For this purpose I have shown a train of double reduction worm gearing operated by the motor comprising a worm 20 110

on an extension of the motor blower shaft, meshing with a worm wheel 21 on a vertical stub shaft 22. On said shaft is a second worm 23 meshing with a second worm wheel 24 journaled in bracket 25. On the shaft of said worm wheel 24 is a cam 26 or other operating member designed to oscillate lever 27 once every revolution (Fig. 3). Said lever is mounted on a shaft 28 having a squared portion 29 clamped to a pair of leaf spring switches 30 and 31 by clamps 32. It will readily be seen that the cam normally holds the contacts closed against the action on the flat springs but that they will be snapped open, as shown in dotted lines in Fig. 5 when the lever 27 passes off the point 33 of cam 26 (Fig. 3). The contacts being opened, the motor will immediately stop. For an understanding of the circuits employed reference is had to the wiring diagram (Figs. 4 and 7-9).

In Fig. 4 both switches 30 and 31 are in both the motor and coil circuits, when the push button 19 is closed the motor and coil being in parallel. It will also be seen that when the push button is open both the motor and coil will still remain in the circuit as long as the switches 30 and 31 are closed. When, however, these switches are open both the motor and coil will be thrown out of circuit. When the push button is closed and while switches 30 and 31 are open, the motor only is thrown into circuit until a revolution of the cam closes switches 30 and 31 as explained.

Fig. 7 shows an arrangement accomplishing substantially the same results. The switches 30' and 31' in this instance, however, are located in slightly different positions in the circuit. In this case the push button 19 and the switch 30' are parallel while the switch 31' is in series with the coil, both coil and switch 31' being in parallel with the motor.

Fig. 8 shows a still simpler arrangement in which the push button 19 and the motor are in series in one circuit and the coil and the two switches 30' and 31' are in series in a parallel circuit. In all of the cases above described, however, it should be noted that the push button is never called upon to handle the heavy currents required for the heating coil but only handles the much smaller current for the motor. Fig. 9 illustrates a very simple form of connections in which the switches 40 and 41 are designed to be manually closed, but are opened by the cam 26 as in the other forms.

From the foregoing description it will be evident that in all but the last form mentioned all the operator need do is to press the push button 19 and hold his hands over the outlet. The motor will thereupon be immediately started thereby closing the switches 30, 31 energizing the heating coil.

The motor will then continue to run for a predetermined interval which is determined by experiment to be sufficient for drying the hands and then will be automatically cut off and the circuit of the coil broken by the opening of switches 30 and 31.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention what I claim and desire by Letters Patent is:

1. In a drying device for the hands and face, a motor, a blower and a case therefor, having an inlet and an outlet, a heating coil located within said outlet, and a completely enveloping cover member having an outlet coinciding with said blower case outlet and arranged to enclose and contain said blower, blower case and motor.

2. In a drying device for the hands and face, a housing having an outlet, a motor driven blower within said housing, a heating coil located within said housing, adjacent this outlet, a manually operated switch also on said housing for energizing said coil and starting said blower, and means operable by said motor for stopping said blower and deenergizing said coil after a predetermined interval of time.

3. In a drying device for the lavatory, the combination with a motor driven blower, an electrically heated coil and a common casing therefor, of manually operated means for closing a circuit or circuits to cause energization of the motor and coil, reduction gearing operated by said motor and a switch also in said casing operable by said gearing for breaking said motor and coil circuits after a predetermined number of revolutions of said motor.

4. In a drying device for the lavatory, the combination with a motor driven blower and an electrically heated coil, of manually operated means for closing a circuit or circuits to cause energization of the motor and coil, double reduction worm gearing operated by said motor, and a switch also in said casing operable by said gearing for breaking said motor and coil circuits after a predetermined number of revolutions of said motor.

5. In a drying device for the hands and face, the combination of a motor driven blower and an electrically heated coil with

- a normally open manually operated motor switch, a normal open motor operated coil switch adapted to simultaneously close the circuit of said motor and short circuit said 5 manually operated motor switch and after a predetermined interval of time to open the circuits of both motor and coil.
6. In a drying device for the hands and face a housing having an outlet, a motor driven blower within said housing, a heating coil located within said housing adjacent this outlet, a manually operated switch also on said housing for energizing said coil and starting said blower, and means operable by 10 said motor for stopping said blower and de-energizing said coil after a predetermined interval of time, a fusible member electrically connected in series with said coil and physically located adjacent to said coil 15 and within said outlet.
7. In a drying device for the hands and face the combination of a motor driven blower, an electrically heated coil, contact switch electrically connected with said motor and coil with means operable by said 20 motor for opening said switch after a predetermined number of motor revolutions.
8. In a drying device for the hands and face the motor driven blower and case therefor having an inlet consisting of a co-extensive opening about the periphery of the cover and supporting base and an outlet, a heating coil located within said outlet, and a completely enveloping cover member having an outlet coinciding with said blower 25 case outlet and arranged to enclose and contain said blower, blower case and motor.

In testimony whereof I have affixed my signature.

WALTER O. LUM.
